CLAIM

The ornamental design for a handle for a hand tool, as shown and described.

DESCRIPTION

FIG. 1 is a perspective of a handle for a hand tool in accordance with the invention showing in broken lines the shaft of a screwdriver which is one use for the present invention;

FIG. 2 is a side elevational view thereof, the opposite side being identical;

FIG. 3 is a front elevational view thereof, the rear elevational view being identical;

FIG. 4 is a top plan view thereof; and,

FIG. 5 is a bottom plan view thereof.

The screwdriver shaft depicted by means of broken lines in FIGS. 1-3 has been shown for illustrative purposes only and forms no part of the claimed design.
